US0D1065537S

(12) **United States Design Patent** (10) Patent No.: **US D1,065,537 S**
Mauzerall et al. (45) Date of Patent: ** Mar. 4, 2025

(54) **FILTER SEPARATOR**(71) Applicant: **SteriCUBE Surgical Systems, LLC**, Grapevine, TX (US)(72) Inventors: **Michele Mauzerall**, St. Petersburg, FL (US); **Maryellen Keenan**, Nutley, NJ (US)(73) Assignee: **STERICUBE SURGICAL SYSTEMS, LLC**, Grapevine, TX (US)(**) Term: **15 Years**(21) Appl. No.: **29/954,950**(22) Filed: **Jul. 30, 2024**(51) LOC (15) Cl. **24-01**

CLAIM

The ornamental design for a filter separator as shown and described.

DESCRIPTION

FIG. 1 is a top, front perspective view of a filter separator showing our design.

FIG. 2 is a front view of the filter separator thereof.

FIG. 3 is a back view of the filter separator thereof.

FIG. 4 is a right side view of the filter separator thereof.

FIG. 5 is a left side view of the filter separator thereof.

FIG. 6 is a top view of the filter separator thereof; and,

FIG. 7 is a bottom view of the filter separator thereof.
